UNITED STATES PATENT OFFICE.

SYLVESTER H. PETTENGILL, OF ROCK RAPIDS, IOWA.

PLASTIC-BLOCK-MAKING MACHINE.

Application filed December 10, 1921. Serial No. 521,448.

To all whom it may concern:

Be it known that I, SYLVESTER H. PETTENGILL, a citizen of the United States, and resident of Rock Rapids, in the county of Lyon and State of Iowa, have invented a new and useful Plastic-Block-Making Machine, of which the following is a specification.

My invention is a plastic block making machine and its all important object is to provide a machine or mold which will form the block and otherwise fashion the same with comparative ease and which, at the same time, will not be laborious to operate.

A further object of the invention is to provide a block making machine or mold which is so constructed as to render the handling of the concrete or other plastic material unnecessary while the machine or mold is being operated.

It is also an object of the invention to provide a machine of this character wherein the various steps necessary in making the block can be carried out by a single workman.

Another general object of the invention is to provide a mold or block making machine which is simple in construction, consists of few parts, can be manufactured and sold at a nominal cost and will be comparatively simple to operate.

With the preceding and other objects and advantages in mind the invention consists in the novel combination of elements, constructions and arrangements of parts and operations to be hereinafter referred to in detail, claimed, and illustrated in the accompanying drawings, wherein:

Figure 1 is a side elevation of a block making machine constructed in accordance with my invention, the dotted line illustrating the mechanism in operated position;

Figure 2 is a similar view of the machine in the act of forming a block, parts being broken away;

Figure 3 is a front elevation having parts broken away;

Figure 4 is a top plan view of the machine;

Figure 5 is a fragmentary detail view of the latch mechanism embodied in the invention.

Referring in detail to the drawings wherein like characters of reference designate like parts throughout the several

views, the numeral 5 designates a vertical standard or base upon which the mold box 6 is slidably mounted. This mold box 6 includes end walls 7 which extend along the opposite vertical faces of the standard or base 5 and are formed with laterally disposed ears 8 with which horizontal rods 9 are connected. A bottom 10 for the mold box 6 is carried between the end walls 7, and, when the mold or machine is in the position shown in Figure 3, rests upon the upper face of the vertical standard or base 5.

Mounted upon one side of the base or standard 5 is a horizontal shelf 11, upon which a table 12 is supported. Normally resting on the table 12 is a bottomless hopper 13 for containing the concrete or other plastic material. The hopper 13 is provided with pivoted end walls 14 which are normally disposed in divergent relation and are adapted to be swung to a vertical position when it is desired to dump the entire contents of the hopper. In order to operate the end walls 14, a hand lever 15 is pivoted intermediate its ends to one of the side walls of the hopper, and connecting the opposite ends of this lever are operating rods 16 which have pivotal connection with the upper ends of the end walls 14. Supported at the opposite side of the standard or base 5 is a platform 16' upon which the finished block is adapted to rest.

In order to swing the hopper 13 to overlie the mold box, as shown in dotted lines in Figure 1, a pair of substantially vertically disposed links 17 are provided and which have their lower ends pivoted to the base or vertical standard 5, as indicated at 18, while their upper ends are operatively connected with the side walls of the hopper through the medium of slot and pin connections 19. Rearwardly and angularly disposed handles 19' are rigidly connected with the links 17. It will be seen that upon forward movement of the handles 19' the hopper 13 will be swung forwardly to register with or overlie the upper end of the mold box 6. When in this position the lever 15 is rocked to swing the end walls 14 to a vertical position to cause the plastic material to drop into the mold box.

The opposite side faces of the vertical standard or base 5 are provided with vertically extending grooves or guideways 20 in which blocks 21 are slidably mounted, the latter being rigidly connected with the inner

faces of the end walls 7. Extending transversely through the lower end of the base or standard 5 is a rock shaft 22, to the ends of which toggle levers 23 are connected, 5 these levers being operatively connected with the blocks or slides 21, as indicated at 24. A handle 25 is fixed to the rock shaft 22 and is normally in the position shown in Figure 1. Upon rocking the lever 25 rearwardly 10 the mold box 6 will be lifted through the medium of the toggle connections above mentioned.

A substantially V-shaped bracket 26 is supported directly above the mold box 6 15 and pivoted to one leg of this bracket is a normally substantially horizontally disposed operating lever 27, the free end of this lever being normally urged upwardly by a contractile spring 28. Pivoted to the lever 28 20 is a vertical rod or stem 29, provided with a collar 30 adapted to be engaged by a pivoted latch element carried by the apex of the bracket 26. One end of this latch element 31 is weighted as at 32. Thus, when the rod 25 or stem 29 is moved downwardly by the lever 27 the nose of the latch element will fall 30 against the collar 30, as shown in Figure 2, and thereby hold the stem or rod 29 in lowered position against the tension of the spring 28. Pivoted to the lower end of the rod or stem 29 is an elongated member 33 35 which carries pairs of divergent arms 34, terminating at their ends in feet 35, which are adapted to engage a follower 36 arranged in the mold box 6. In order to return the elongated member 33 to the position shown in Figure 1 a cable or other flexible element 37 is provided, which passes over pulleys 38 and has one end attached 40 to the elongated member 33 and its opposite end weighted as at 39.

In the operation of my improved plastic block making machine or mold the hopper containing plastic material is swung to the 45 dotted line position shown in Figure 1 and the plastic material ejected therefrom by manipulation of the end walls, as above set forth. The hopper is then swung back to rest on the table 12 and the follower 36 50 superposed on the "batch." The operator then swings the elongated member 33 downwardly to dispose the legs 34 in a vertical position and then moves the lever 27 downwardly to lower the legs 34 into the mold 55 box 6, in which position they are held by the latch 31 engaging the collar 30 as above outlined. The mold box is then raised vertically through the medium of the operating lever 25 to strip the mold box from the 60 block. After the block has been thus stripped it is moved laterally from beneath the mold box, as indicated in dotted lines in Figure 2, and deposited on the shelf or platform 16'. The handle 25 is now re- 65 turned to normal position to lower the mold

box. The member 33, carrying the legs 34, is returned to horizontal position by the weighted cable 37 and the latch 33 disengaged from the collar 30 to permit the lever 27 to return to normal position.

It is to be understood that the form of my invention herein shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States, is:

1. A block making machine comprising a vertically movable mold box, a normally substantially horizontally disposed lever pivoted above the mold box, a vertical member depending therefrom, an elongated member pivoted to the lower end of the vertical member, a plurality of feet carried by the latter and adapted to engage a follower placed upon the upper face of the "batch" in the mold box, locking means for holding the vertical member rigid, means for raising the mold box to form the press, means for swinging the feet to inoperative position after the subsequent lowering of the mold box, and means for normally returning the lever to its initial position.

2. A block making machine including a vertical standard, a mold box having end walls straddling the standard slidably connecting the mold box therewith, a follower, and means for elevating the box about the follower.

3. A block making machine including a vertical standard, a mold box having end walls straddling the standard slidably connecting the mold box therewith, a follower, and blocks slideable upon the standard to co-operate with the box for elevating the box about the follower.

4. A block making machine including a vertical standard, a mold box having end walls straddling the standard slidably connecting the mold box therewith, a follower, the standard being provided at opposite sides thereof with vertical grooves, and blocks slideable in said grooves to co-operate with the box for elevating the box about the follower.

5. A block making machine including a vertical standard, a mold box having end walls straddling the standard slidably connecting the mold box therewith, a follower, the standard being provided at opposite sides thereof with vertical grooves, blocks slideable in said grooves to co-operate with the box, a rock shaft upon the standard, levers carried by said shaft, links connecting said levers with the blocks, and means for

rocking said shaft and raising the blocks to elevate said box.

6. A block making machine including a mold box, means for elevating the box, a vertical rod above the box, a follower abutment member pivoted to the lower end of said rod to swing downwardly thereon to active position, and means for automatically swinging said member upwardly independently of the rod to inactive position.

7. A block making machine including a mold box, means for elevating the box, a vertical rod above the box, a follower abutment member pivoted to the lower end of said rod to swing downwardly thereon to active position, and a counterweight connected with said member for automatically swinging said member upwardly independently of the rod to inactive position.

20 8. A block making machine including a mold box, means for elevating the box, a vertical rod above the box, means for depressing or elevating the rod, a follower abutment member pivoted to the lower end of said rod to swing downwardly thereon to active position, and means for automatically

swinging said member upwardly independently of the rod to inactive position.

9. A block making machine including a mold box, means for elevating the box, a vertical rod above the box, means for depressing or elevating the rod, means for automatically locking the rod depressed, a follower abutment member pivoted to the lower end of said rod to swing downwardly thereon to active position, and means for automatically swinging said member upwardly independently of the rod to inactive position.

25 10. A block making machine including a mold box, means for elevating the box, a vertical rod above the box, a lever for depressing or elevating the rod, a spring acting upon the lever for elevating the rod, a pivoted latch for automatically locking the rod depressed, a follower abutment member pivoted to said rod to swing downwardly thereon to active position, and means for automatically swinging said member upwardly to inactive position.

SYLVESTER H. PETTENGILL.
